UNITED STATES PATENT OFFICE.

WILLIAM ANDREW HARRIS AND BENJAMIN SAMUEL HAMPTON HARRIS,
OF GREENVILLE, SOUTH CAROLINA, ASSIGNORS TO THE HARRIS MANU-
FACTURING COMPANY, OF GREENVILLE, SOUTH CAROLINA, A CORPO-
RATION OF SOUTH CAROLINA.

COMBINED TRAIN SIGNAL AND INDICATING APPARATUS.

No. 846,306.

Specification of Letters Patent.

Patented March 5, 1907.

Application filed March 23, 1904. Renewed June 6, 1906. Serial No. 320,451.

To all whom it may concern:

Be it known that we, WILLIAM ANDREW HARRIS and BENJAMIN SAMUEL HAMPTON HARRIS, citizens of the United States, and residents of Greenville, in the county of Greenville and State of South Carolina, have made certain new and useful improvements in Combined Train Signal and Indicating Apparatus, of which the following is a specification.

10 This invention is an improvement in train signaling apparatus, and especially in train signaling apparatus designed for use on freight-trains, which are frequently, if not usually, made of such length that the sounds 15 of the whistle given by the engineer to indicate the reception of signals will not reach back to the caboose, the present invention relating to means whereby the engineer may signal back to the conductor or other train- 20 man in the caboose the signals which have been received by the engineer or any other signal's desired, the objects being to establish signaling communication by which signals may be reliably sent back and forth between 25 the caboose and the engine-cab; and the invention consists in certain novel constructions and combinations of parts, as will be hereinafter described and claimed.

In the drawings, Figure 1 is a side elevation, partly broken away, illustrating in diagrammatic view our invention applied to a freight-train. Fig. 2 is a detail elevation, partly in section, of the apparatus, showing the operating devices in connection with the 35 signals and signal-pipe at the opposite ends of the train.

By our invention we employ in connection with an independent signal-pipe, which has no connection whatever with any of the devices of the brake or other devices carrying pressure, means at the opposite ends of the train for imparting impulses to the fluid in the signal-pipe, so that the conductor in the caboose or the engineer in the cab can signal 45 with certainty to the other by means of the impulses positively imparted to the fluid in the independent signal-pipe, as will be more fully described hereinafter.

The signal-pipe A is independent of the 50 brake-pipe or other device carrying pressure in the train, and the invention can be readily

applied to trains equipped with modern air-brakes as well as to cars which are not provided with such improved equipment. The signal-pipe sections of the cars may be 55 coupled between the cars by suitable coupling sections A', and signals B and B' are provided, respectively, in the caboose and the locomotive-cab for operation by impulses imparted to the fluid in the signal-pipe. These signal 60 devices B may be of the form shown, such signal devices forming a part of the subject-matter of a separate application for patent executed and filed of even date herewith, so that the signal devices need not be described 65 in detail herein, it being understood that they are arranged and adapted to be positively operated by impulses imparted to the fluid in the signal-pipe.

Operating devices C and C' are provided in 70 the caboose and in the locomotive-cab for imparting impulses to the fluid in the signal-pipe. These operating devices are constructed alike, and each comprises a cylinder D, which communicates near one end at D' 75 with its respective signal and at its other end at D² with the signal-pipe section on the car or caboose which supports the particular operating device. It will thus be noticed that the cylinders D form practically a part of the 80 signal-pipe—that is to say, when the operating device C' is operated to produce an operation of the signal B the cylinder D, in connection with said signal B, forms a part of the signal-pipe for transmitting the impulses to 85 operate such signal B, and vice versa—so that when one operating device is acted upon by the conductor or the engineer the cylinder D of the other operating device forms a part of a signal-pipe for conducting the impulses to 90 operate the desired signal.

The cylinder D at its end adjacent to its port D', communicating with its signal, is provided with a discharge opening or vent D² for the escape of air in readjusting the piston presently described to normal position, and the abutment or stop D⁴ for limiting the movement of the piston toward such end of the cylinder is so located relatively to the port D' that the piston when moved to its 100 normal position, as shown in Fig. 2, will pass beyond to the port D', so such port will com-

municate with the body of the cylinder and the piston will operate as a valve or closure for the venting-port D³, closing such end of the cylinder, except as to its communication 5 through the port D' with the signal. The piston E operates in the cylinder D, and when moved from the position shown in Fig. 2 to its opposite position it will force the air in the cylinder D out through the port D² to 10 the body of the signal-pipe, and thus produce a movement or impulse of the air in the signal-pipe which will operate the signal at the opposite end of the train, it being understood that when the operating device at one end of 15 the train is being operated the piston E in the cylinder at the opposite end of the train will be adjusted to normal position, in which it closes the vent D³ and opens communication between the port D' and the body of the cylinder, as will be understood from Fig. 2 of the 20 drawing. The piston E has its rod E' provided with a handle E², by which the piston may be moved back and forth in the cylinder, a spring-latch F, as best shown in Fig. 2, 25 being provided for holding the piston in its normal position, so it will not jar out of such position by the movement of the train or from other causes, but will always remain in normal position, except when moved positively 30 therefrom by the operator, whether he be the engineer or the conductor.

Now it will be understood that the cylinders at both ends of the train form practically a part of the signal-pipe and the signals at 35 both ends of the train form practically open ends of the signal-pipe, so that in operation one or more impulses will be imparted to the air in the signal-pipe by the desired number of operations of the proper piston, and such 40 impulses will give corresponding operations to the signal at the opposite end of the line of signal-pipe. Thus in operation if the piston E at one end of the signal-pipe be operated once it will positively produce a single operation 45 of the signal device at the opposite end of the train, and each succeeding operation of the piston will correspondingly operate the signal device. Thus we secure a positive operation 50 of the signal corresponding to the number of times the piston of the operating device is moved in its cylinder, the operator, whether he be the engineer or the conductor, drawing the piston quickly outward and then returning the piston to its normal position 55 and repeating such operation as many times as may be necessary in order to transmit the signal desired. In the return movement of the piston the air in the cylinder will be vented through the discharge D³, which is 60 made sufficiently larger than the port D' to permit the escape of the air without causing any sounding or operation of the signal adjacent to the particular piston being operated.

It will be noticed the port D³ is beyond the 65 port D', so that the piston E at one end of the

signal-pipe will not operate the signal at the other end of said pipe until the piston in the cylinder adjacent to the signal to be operated is moved beyond the port D' of said cylinder to the position shown in Fig. 2 of the drawings. 70

By the invention it will be noticed that when the engineer receives a given signal from the caboose he can by operating the piston E in the engine-cab return such signal to 75 the conductor in the caboose, so the conductor will know the engineer has not only received, but has properly understood, the signal which has been transmitted to him, which is an important factor in preventing 80 accidents in the running of trains.

The signal devices, as before suggested, are included in the subject-matter of a separate application for patent executed and filed of 85 an even date herewith. It may be well, however, to state that such signaling devices include signals arranged for operation successively by impulses imparted to the air in the signal-pipe, one impulse transmitting a single signal having a definite meaning, two impulses transmitting a second signal, and so on, any desired code of signals being employed. 90

Having thus described our invention, what we claim as new, and desire to secure by Letters Patent, is— 95

1. The improvement in signaling apparatus herein described comprising the signals at the opposite ends of the line, the cylinders connecting near one end with said signals, the signal-pipe proper connecting with the other ends of the cylinders whereby the cylinders form practically parts of the signal-pipe for conducting impulses from said pipe to their respective signals, the ends of the cylinders adjacent to the ports communicating with the signals having venting or discharge openings, the pistons operating in their cylinders and movable in normal position to points where they close the venting or discharge openings in said cylinders and open communication between the cylinders and the ports leading to their respective signals, the piston-rods and handles and spring-latches for securing the pistons in normal position. 110

2. The combination of the signal-pipe, the signals at the opposite ends of the signal-pipe, and the devices for operating the signals having cylinders communicating at one end with their respective signals and at their other ends with the signal-pipe whereby communication between the signal-pipe and the signals is effected through the respective cylinders. 120

3. A signaling apparatus comprising a signal-pipe, a signal or signals arranged for operation by impulses imparted to the fluid in the signal-pipe and an operating device having a cylinder communicating at one end with the signal-pipe and at its other end with 125 130

the signal and a piston in said cylinder and adapted for operation whereby to produce impulses in the signal-pipe.

4. The combination with the signal of an operating device having a cylinder provided at one end with a discharge opening or vent and adjacent to said end with a port communicating with the signal and the piston in the cylinder and movable to a point beyond the port communicating with the signal when said piston is adjusted to position to close the venting or discharge opening of the cylinder and connections between said cylinder and a signal-pipe whereby the piston and cylinder may be operated to produce impulses in the signal-pipe and the cylinder may be utilized as a conduit for the passage of impulses from the signal-pipe to the signal.

5. A signaling apparatus comprising an independent train-pipe carrying atmospheric pressure, signals and indicators operating in correspondence with said signals at the opposite ends of and forming open ends at such opposite ends of the signal-pipe and means for imparting impulses to the fluid in the signal-pipe whereby to operate the signals and indicators.

6. A signaling apparatus comprising a signal-pipe, signals at the opposite ends of the pipe and through which open communication between the atmosphere and the signal-pipe is normally established, indicators acting in correspondence with said signals and means for imparting impulses to the fluid in the signal-pipe for operating the signals and indicators at one or the other end thereof.

7. A signaling apparatus comprising the opposite signals, the signal-pipe, the cylinders between the signal-pipe and their re-

spective signals, the pistons in said cylinders and adjusted normally to position to open communication between the signal-pipe and their respective signals and the pistons in said cylinders being adapted for imparting impulses to the fluid in the signal-pipe for operating the signal at the opposite end of the signal-pipe.

8. In a signaling apparatus an operating device comprising a cylinder having a vent or discharge opening at one end and provided near said end with a port for communication with the signal and at its opposite end with a port for communication with the signal-pipe and the piston operating in said cylinder and movable in normal position to a point where it will close the vent or discharge-opening in the end of the cylinder and will establish communication between the signal-port and the body of the cylinder.

9. The combination with the signal, and the cylinder having near one end a port communicating with the signal and also having at such end a vent or discharge-port, and provided at its other end with an outlet-port and the signal-pipe communicating therewith, of the piston operating in the cylinder and movable in normal position to a point where it will close the vent or discharge-port from the cylinder and open communication between the signal-pipe and the body of the cylinder, the piston-rod and a latch for holding the piston from accidental displacement from its normal position.
